ATTORNEY.

UNITED STATES PATENT OFFICE.

CHARLES CLARKE-BRUFF, OF COALPORT, ENGLAND.

COVERED HOLLOW WARE.

1,384,302.

Specification of Letters Patent. Patented July 12, 1921.

Application filed July 9, 1920. Serial No. 395,084.

To all whom it may concern:

Be it known that I, CHARLES CLARKE-BRUFF, a subject of the King of Great Britain, residing at Coalport, England, have 5 invented certain new and useful Improvements in and Relating to Covered Hollow Ware, of which the following is a specification.

This invention relates to improvements 10 in and relating to covered hollow ware, and being particularly applicable to fisticl articles it will be hereinafter described in that application.

In particular the present invention aims to 15 obviate that incongruous combination of a metal lid or cover and a fisticl vessel which is emphasized in such vessels as covered jugs and the like; also to counter these difficulties of manufacture which arise from 20 irregularities of size and figuring, these irregularities requiring more or less individual fitting of each and every metal cover to its vessel, and unless the manufacturer has facilities on his own works to 25 produce and fit the covers, the vessels must be despatched to makers of these metal covers whereby production costs are burdened with the costs of packing and transport, and with the delay and risk of damage in transit.

To the foregoing ends the improvements 30 according to the present invention are directed to that type of vessel fitted with a loose removable lid or cover having a rigid lip or verge in which upon the vessel being 35 held at an inclination the lid or cover is held at points on the front or delivery side of the vessel and the back of the lip or verge of the lid or cover comes or bears against the interior of the neck of the vessel where- 40 by the lid or cover is prevented from falling off the vessel.

According to the present invention the engagement between the lid or cover component and the vessel component from op- 45 posite plain faced wall parts on the front or delivery side of the vessel is effected by elastic means as local friction grips applied to one component, for example, the rigid lip or verge of the fisticl lid or cover, such elastic 50 means frictionally reacting with the vessel to form a plain face friction grip lock to hold the lid or cover at the front while the back of the lip or verge by coming or bearing against the interior of the neck of the 55 vessel completes the lock, thus preventing

the lid from falling forward, and securing it against accidental displacement during the inclination of the vessel. Moreover by such frictionally reacting means, for example, rubber stud-like members, slack fit- 60 ting of a fisticl lid or cover may be neutralized and a desirable tightness of the lid or cover on its vessel, insured, even to the ex- 65 tent that a falling backward as well as a falling forward of the lid is hindered or prevented when the vessel is completely inverted.

The elastic members, for example, rubber studs applied to the lip or verge of the lid or cover so as to be capable of frictionally 70 engaging the vessel from opposite points on the delivery side of the vessel, will set up a grip lock of the lid or cover sufficiently effective to hold the lid or cover at these points and prevent the lid or cover from 75 falling off when the vessel is tilted, or even completely inverted, as above described. At the same time the lid or cover may be quite easily removed when required.

Thus let the studs be located on a chord 80 which divides the plan or inscribed circle of a cylindrical or equivalent vessel, as a jug for example into unequal segments of which in the case of a jug, for example, the small segment is on the delivery side of the ves- 85 sel, it will be seen that the lid or cover can be quite easily removed, without using more force than is required to lift up the lid or cover by tilting it backwardly from the de- livery side, the reason for this being that 90 the arcuate path of the studs thus produced cuts across chords of increasing length.

As further conducing to safety the mouth of the vessel may be sloped so that it rises to the highest point on the delivery side 95 of the vessel.

For the purpose of enabling the improve- 100 ments under the present invention to be more readily understood, reference is hereinafter made to the accompanying drawings, in which an application of the invention to a jug is shown, and in which:

Figure 1 is a view in profile and partly in section of a jug provided with a lock or safety lid in accordance with the present 105 invention.

Fig. 2 is a section on the line $x-y$ of Fig. 1.

In carrying the present invention into practical effect, it is convenient, in the case 110

of a jug *a* with lip *b*, to form the lip or verge *c* of the loose lid or cover *d* of the shape or contour of a horse-shoe.

That part of the lip or verge *c* remote from the lip *b* is preferably slightly lengthened, while the part of the lip or verge *c* nearest the lip *b* is fitted on the opposite sides of a plane passing medially through the lip, body, and handle of the jug, with two or more rubber studs *e*, *e'*, adapted to take up any slackness in fitting and to grip the interior surface of the wall of the jug especially when the vessel is tilted.

The studs *e*, *e'* are illustrated as constituted of double flanged stems which are sprung into perforations in the wall of the lip or verge *c* so as to be retained therein by the companion flanges, but any suitable or appropriate method of fastening the studs in position may be adopted without departing from the present invention.

Obviously the studs or like grip means may be fitted to the wall of the vessel instead of to the lid or cover.

25 The mouth of the vessel may if desired be sloped as shown for further security but sloping of the mouth of the vessel is not essential for the purpose of the present invention.

30 As conducing to additional safety that part of the lip or verge of the lid or cover which is remote from the lip *b* and the corresponding part of the neck of the vessel *a* may be sloped outwardly.

35 What I claim is:

1. In a covered vessel of the type described, in combination, a vessel component, a loose removable cover component, said cover component having a rigid verge the back of which is adapted to bear against the interior of the neck of the vessel to counter a tilting movement of said cover component toward the pouring side of the vessel, and said components, on the pouring side thereof, having corresponding plain faced wall parts with appertaining intermediate elastic means as local friction grips on

one component for frictionally reacting with the other component to form a plain face friction grip lock. 50

2. In a covered vessel of the type described, in combination, a vessel component, a loose removable cover component, said cover component having a rigid verge the back of which is adapted to bear against the interior of the neck of the vessel to counter a tilting movement of said cover component toward the pouring side of the vessel, and said components, on the pouring side thereof, having corresponding plain faced wall parts with appertaining elastic members in apertures of the verge of said cover component as local friction grips for frictionally reacting with the vessel component to realize a plain face friction grip on the pouring 65 side of the vessel. 60

3. A loose cover for a vessel of the type described with a plain interior wall surface, said cover having a rigid verge the back of which is adapted to bear against the interior 70 of the neck of the vessel to counter a tilting movement of said cover toward the delivery side of the vessel, and elastic members as local plain face friction grips in apertures 75 of the verge of said cover adapted to form a friction grip lock on the plain interior face of the vessel on the pouring side thereof. 75

4. A loose cover for a vessel of the type described with a plain interior wall surface, said cover having a rigid verge the back of 80 which is adapted to bear against the interior of the neck of the vessel to counter a tilting movement of said cover toward the delivery side of the vessel, and elastic members as local plain face friction grips in apertures 85 of the verge of said cover adapted to form a friction grip lock on the plain interior face of the vessel on the pouring side thereof, said elastic members each consisting of rubber studs with disk-like head and foot 90 retaining portions. 90

In testimony whereof, I affix my signature.

CHARLES CLARKE-BRUFF.
